UNITED STATES PATENT OFFICE.

THOMAS F. McKEON, OF FENTON, MICHIGAN.

FENCE POST.

Application filed June 12, 1924. Serial No. 719,478.

My invention relates to a new and useful improvement in a fence post, and particularly that class of fence post made from concrete or other hardening plastic material. 5 An object of the invention is the provision of a fence post made from such material, having staple receiving means so that the wire may be easily and quickly attached to the post without necessitating the employment 10 of any other attaching means than the usual staple adapted for this purpose.

Another object of the invention is the provision in a fence post made from the material mentioned having staple fastening 15 means mounted in the fence post and provided with securing means imbedded in the post itself.

Another object of the invention is the provision of a reinforced concrete fence post 20 having reinforcing strips extending longitudinally of the post and provided with securing means adapted for holding the reinforcing parts in relative position preliminary to the pouring of the plastic material 25 about the reinforcing strips.

Other objects will appear hereinafter.

The invention consists in the combinations and arrangements of parts hereinafter described and claimed.

30 The invention will be best understood from a reference to the accompanying drawings which form a part of this specification and in which,

Fig. 1 is a front elevational view of the 35 invention,

Fig. 2 is a rear elevational view of the invention,

Fig. 3 is a sectional view taken substantially on line 3—3 of Fig. 1,

40 The invention, in its preferred form, comprises a fence post 7, made from concrete or the like, having an ornamental cap or top 8 at its upper end. Imbedded in the concrete post 7, so as to have its outer face lie flush with the face of the post, is a board strip 9. Embracing the strip 9 and projecting into the concrete are U-shaped retaining clips 10 made from some suitable wire and having the ends 11 and 11' flared outwardly from 45 each other, so as to provide means for normally resisting their removal from the post after the plastic material which has been poured around the same has hardened. Extending longitudinally of the post are a pair 50 of reinforcing members 12 and 12'. These members extend substantially throughout the 55 length of the post and are held together by means of U-shaped clips 13 which embrace two members, the outer ends of the clips being outwardly flared as at 14 and 14'. 60

It will be noted that the wooden strip extends along the post from a slight distance above the ground close to the upper end of the post. The purpose of this strip is to provide staple receiving means at that portion of the post, to which a wire may be fastened. It is, of course, evident that the length of this strip or the particular location of it is optional with the one making the post and depends largely upon the use to 70 which the post is to be put. It is also apparent that this strip of wood may be made in sections, if desired.

While I have illustrated and described the preferred form of structure, I do not wish 75 to limit myself to the precise form of structure shown, but desire to avail myself of such variations and modifications as come within the scope of the appended claim.

Having thus described my invention, what 80 I claim as new and desire to secure by Letters Patent is:

A concrete fence post comprising a main body portion; a pair of longitudinally extending spaced reinforcing strips, of a width 85 slightly less than the thickness of said post, embedded in said post and having their longitudinal edges within the marginal limits of said post; U-shaped clips for embracing said strips at their longitudinal edges for 90 retaining the same in operative relative position, the outer ends of said U-shaped clips being flared outwardly for preventing their removal from the concrete poured around said strips; a wooden strip embedded in said 95 main body portion between said reinforcing strips and having its inner face projecting inwardly of one of the longitudinal edges of said strips, the outer face of said wooden strip lying flush with one of the faces of said post; U-shaped clips embedded in said post, the legs of said U-shaped clips engaging opposite faces of said wooden strip in said post and the bight of said U-shaped clips lying snugly in engagement with the outer 100 surface of said wooden strip, the ends of said legs of said U-shaped clips being angularly turned for preventing their removal from said post.

In testimony whereof, I have signed the 110 foregoing.

THOMAS F. McKEON.
